DESIGN FOR A LADY'S COSTUME.

2104

2104

UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,317, dated May 15, 1888.

Application filed April 20, 1888. Serial No. 271,347. Term of patent 34 years.

To all whom it may concern:

Be it known that I, ELLEN MORAN, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a round walking-skirt and a polonaise. The skirt displays a kilted drapery reaching to the edge of the gores, a long oval tablier exhibiting draping plaits in its side edges, and a full back drapery falling even with the edge of the skirt and displaying bournous loops and backward-turning

plaits. The polonaise exhibits close-fitting fronts opening over a short pointed vest and falling in long tabs at the sides nearly to the edge of the skirt; a close-fitting basque-back displaying underfolded plaits below the waist-line of the middle three seams; revers turning from the front edges of the fronts above the waist-line, a standing collar, and coat-sleeves. 25

What I claim as my invention, and desire to secure by Letters Patent, is—

The design for a lady's costume, as shown in the engraved prints accompanying this specification.

ELLEN MORAN.
